FACSIMILE TRANSMISSION APPARATUS

Harold Carlson, Tuckahoe, N. Y., assignor to The Associated Press, New York, N. Y., a corporation of New York

Application April 8, 1938, Serial No. 200,895

17 Claims. (Cl. 178—7.4)

This invention relates to a facsimile transmission apparatus and more particularly to a recorder for a facsimile telegraph system.

An object of the invention is the provision of a simplified apparatus of high efficiency at a low cost.

Other objects will appear in the accompanying description given with the aid of the drawings, of which

10 Figure 1 is a plan view of the invention, Figure 2 is a plan view of the apparatus beneath the base, given with the base inverted,

Figure 3 is a vertical section taken through 3—3 of Figure 1,

15 Figure 4 is a vertical section taken substantially along the lines 4—4 of Figure 1,

Figures 5 and 6 are sections showing details of the mechanism associated with the lead screw and lead nut,

20 Figures 7 and 8 show details of the scanning cylinder together with its cover,

Figure 9 is a section taken through 9—9 of Figure 1,

25 Figures 10 and 11 give details of the light tight slot in the base through which the scanning light is projected,

Figure 12 is a plan view of a device for loading a scanning cylinder enclosed in a light proof shell or hollow cylinder with a sheet of sensitized

30 material,

Figures 13 and 14 illustrate the method of securing a sensitized sheet to the scanning cylinder,

Figure 15 shows a tool for operating the film holding strip on the scanning cylinder,

Figure 16 is a section taken through 16—16 of Figure 12,

Figure 17 is a section taken through 17—17 of Figure 12,

40 Figure 18 is a detailed view of the pressure roller mounting in the loading device,

Figure 19 is a section showing the cylinder and guideway therefor in the loading device.

Referring now to Figure 1 of the drawings 45 which shows a motor 1 secured to the upper surface of a hollow base 2, the motor shaft being connected by means of a positive clutch 4, controlled by magnets 5 to a shaft 6 arranged to rotate in suitable bearings 7.

50 At one end of the shaft, Figures 1, 7, and 9, is secured a disc 8 provided with a pin 9 adapted to enter a slot 10 in a second disc 11 secured to shaft 12 formed integrally with flanged end piece 13 of a hollow scanning cylinder 14, the cylinder 55 being provided at its opposite end with a second

end piece similar to 13 which is integral with shaft 15, the latter as well as disc 11 being spotted or countersunk in order that the cylinder may be rotatably supported between centers 16 of tailstock 17 and 18 of shaft 6.

Tailstock 17 consists of bracket secured to the base provided with an opening in which spindle 19 is free to reciprocate. A compression spring 20 presses the spindle toward shaft 15, while pin 21 which projects through an L-shaped opening 10 22 in the bracket is used to manually retract the spindle when a drum is being removed or inserted.

Cylinder 14 is provided with a light proof casing of novel design which permits the use of 15 highly sensitive film in the device under ordinary office lighting conditions, a dark room being necessary only for loading and unloading the detachable cylinder assembly which will be described further on. Furthermore the invention 20 provides for an automatically operating shutter for the cylinder casing, which makes it impossible to accidentally expose the sensitized material when a cylinder is being removed or inserted.

Referring particularly to Figure 7 which is a 25 plan view of the cylinder casing partly in section:

End pieces 13 of the cylinder are provided with flanges 30 held against the ends of a metal tube 31 by threaded rod 32.

A deep annular recess 33 is cut into each end-piece, and into this recess extends ring 34 formed integrally with the ends 35 of cylinder casing 36. In each end of the casing is an opening 37 through which shafts 12 and 15 project which makes it possible to rotatably support the cylinder 35 while the casing remains stationary. The arrangement just described also provides a light trap at each end of the cylinder casing.

At the bottom of the casing is a longitudinal slot 38 extending the length of cylinder 14. Casing 36 has a base 39 provided with a longitudinal slot 40 coinciding with slot 38. Base 39 fits over a supporting member 41 provided with a slot 42, (Figures 8 and 10) overlying an opening 43 in base 2.

45 Guides, composed of angle strips 44 are secured to three sides of support 41, the fourth side being open to permit base 39 to slide under the turned over part 45 of the guide strips.

Referring to Figures 7, 8, and 16, casing base 50 50 is shown composed of three strips of metal 50, 51 and 52 secured to each other and also to casing 36. The metal strip 51, however, is cut away for some distance beyond slot 40 on three sides, and the fourth side which will overlie the part of 55

support member 41 to the left of the drawings, in Figure 8 is completely cut away for a distance somewhat greater than the length of slot 40 which provides a recess between strips 50 and 52 into which slides a shutter 53 which when closed renders light proof the part of the casing just referred to.

Shutter 53 is provided with a turned up edge 54 engaged by spring 55 secured by screw 56 to base 39, the spring tending to keep the shutter in the closed position as shown in Figure 8. The shutter also has a series of ears 57 extending downwardly through slots 58 in base strip 52, so located as to engage one edge of support member 41 and cause the shutter to withdraw (Figure 4), against the pressure of spring 55 and open slot 40 when a cylinder is properly positioned in the machine. Likewise, after a scanning operation has been completed, spring 55 closes the shutter as the cylinder assembly is removed from the guides. With this arrangement it is impossible to accidentally cause an undesired operation of the shutter. The upper surface of support 41 is covered with felt 59 to ensure a light proof connection between the cylinder cover and base 2.

The casing is retained in position by means of notches 60, Figure 7, in each end of base 39 which are engaged by detent springs 61, Figure 10, secured to angle pieces 44.

30 Worm 62 on shaft 6, Figure 1, drives worm wheel 63 secured to vertical shaft 64, one end of which turns in bearings 65 in support 7, and the opposite end in bearing 66 in bracket 67 secured to the underside of base 2, Figure 3.

35 Gear 68 on shaft 64 drives gear 69 secured to a threaded shaft or lead screw 70, Figure 2, supported by suitable bearings in brackets 67 and 71, bracket 67 being secured by screws 72 near one end of a longitudinal rib 73 depending from the underside of base 2, while bracket 71 is secured at the opposite end of rib 73 by screws 74 and 75. The bearings for the lead screw are of a suitable anti-friction type, and means are provided at each end of the shaft for adjusting the shaft 45 longitudinally in the bearings, consisting of a strap 76 secured by screws 77 to the respective bearing brackets, the strap supporting an adjusting screw 78 which engages a ball bearing in the end of the lead screw. This method of 50 shaft adjustment is followed in other parts of the machine.

By means of the mechanism described above, the lead screw is driven in fixed relation to the rotation of the scanning cylinder. The function 55 of the lead screw is to provide a uniform longitudinal feed of a casting 80 which carries a lamp and an optical system.

Referring to Figures 2 to 6: Casting 80 which will be referred to as a carriage, is provided at its 60 upper part with arms 81 and 82, the underside of the latter having a bevelled recess 83, Figure 4, which rides on a bevelled rib 84 of a runner 85 secured by screws 86 to rib 73 so that the runner parallels longitudinal slot 43 in base 2.

65 The carriage is supported on the opposite side of slot 43 by a runner 87 secured by screws 88 to rib 89 depending from the underside of base 2. The upper surface of runner 87 is flat and is contacted by a rib 90 on the underside of arm 81.

70 A vertical cylindrical opening 92 extends through casting 80, in the upper part of which is inserted a suitable optical system, and immediately below is a lamp 94 which in the present embodiment closely fits opening 92 and is retained 75 in place by friction.

Both the optical system and the lamp are known devices, the glass bulb of the latter contains a combination of the rare atmospheric gases responsive over a frequency range greater than the band necessary for picture transmission, and has linear illumination-current characteristics. The glow is concentrated within a small definite boundary, at the top of the lamp, and the optical system is positioned so as to most effectively project the light rays onto the sensitized sheet on 10 the scanning drum. The lamp is known commercially as a "crater" lamp and is made by the Westinghouse Company.

The average time for transmitting a press picture is about eight minutes, during which time 15 the carriage is slowly fed by the lead screw away from its normal or starting position. On completion of a picture, in order to save line time, it is desirable that the carriage be quickly returned to its initial position without stopping the motor, 20 or without putting any sudden excessive load on the apparatus which might cause such stoppage. The present invention provides a novel method of engaging and disengaging a lead nut secured to the carriage from the lead screw 25 which permits the carriage to be positioned at will.

Rigidly secured to the carriage casting 80 is a horizontal bracket 100, to which is fastened by screws 101 a member 102 having depending arms 103 holding pivot 104 on which is rotatably supported bar 105 which has in its mid portion an opening 106, and pivoted therein on pivot 107 which is disposed parallel to the lead screw is a vertical rod 108, having a bracket 111 secured at 35 its upper end by nut 109 and threaded section 110. Screws 112 fasten a block 113 to bracket 111. This block has a concave upper surface and has a thread cut therein to fit that of the lead screw. The block will be referred to hereinafter as the 40 lead nut. Spring 114 on rod 108 tends to hold the lead nut in engagement with the lead screw.

The support just described permits the lead nut to have some play in all directions in respect to the lead screw, which is advantageous in that 45 it makes it possible to engage easily and disengage the lead screw and nut by mechanism which will be described below.

During operation, on engagement of the lead screw and lead nut the latter is caused by the 50 rotation of the lead screw to assume a definite fixed position until the parts are manually disengaged. This is accomplished as follows: In Figure 4 the lead screw is shown as rotating in a counterclockwise direction which will tend to 55 press the lead nut towards the right of the drawings where it engages adjusting screw 115 in the rigid upright member 102.

Referring to Figures 4 and 5: A pair of light flat springs 116 secured by screws 117 to bracket 60 100 engage the side of the lead nut and tend to hold it against screw 115. The direction of travel of the carriage when driven is toward the right of Figure 5. The lead screw exerts pressure on the lead nut tending to move it to the right, but the movement of the lead nut in respect to the carriage is definitely limited in this direction by stop screw 118, Figures 5 and 6, in bracket 100. When disengaged from the lead screw, however, the lead nut is free to move a limited distance 70 away from stop screw 118.

Lever 120 secured to cam 121 pivoted to a stud 122 in the carriage is used for the purpose of controlling the engagement of the lead screw and lead nut. Figure 4 shows these parts in 75

engagement. When lever 120 is turned, cam 121 presses downwardly on rod 123 which engages stud 124 in support 105 retracting rod 108, compressing spring 114, and disengaging the lead nut 5 from the lead screw. When the lever is reversed these parts re-engage. A longitudinal slot 125 is provided in base 2 through which the upright part of lever 120 projects.

Referring to Figures 4 and 11: A metal strip 10 126 of J-shaped cross section is secured underneath base 2 on each side of slot 43. These strips extend beyond the ends of the slot and serve as guides for a light tight shutter which 15 consists of a thin strip of bronze 127 having an opening 128 through which a tube 129 carrying the adjustable objective of optical system 93 extends. The length of shutter 127 is such that slot 43 is always covered, irrespective of the 20 position of the carriage. Beyond the ends of guides 126, curved strips of flat metal, 130 and 131 are secured. The thin springy shutter metal 127 is set or strained so as to curl up in either 25 130 or 131, winding up in one and unwinding in the other as the carriage moves.

As previously stated, clutch 4 is controlled by clutch magnet 5. Referring to Figures 2 and 3: The clutch magnet assembly is mounted on a base 140 which is secured to the underside of base 2 by screws 141 extending through elongated 30 holes which permit adjustment. The various parts of the assembly extend upward through an irregularly shaped opening 142 in base 2.

Magnet armature 143 is supported on pivot 144. Armature spring 145 is fastened between 35 stud 146 in the armature and adjusting screw 147. The upper part of the armature is provided with a step, part of which may be engaged by a spring pressed holding pawl 149 pivoted at 150. When magnet 5 is momentarily energized, the 40 step 148 catches under the nose of the pawl which holds the armature against the poles of the magnets. This mechanical locking arrangement may be released by pressing button 151 which engages one arm of the pawl elevating the nose thereof 45 until it becomes disengaged from the armature step 148.

Clutch 4 consists of a toothed driving wheel 160, (Figures 1 and 3), secured to shaft 3 of the motor, and a driven part consisting of a disc 161 secured to shaft 6. Connection between the driving and driven parts is effected by pawl 163 pivoted to disc 161 by screw 164. Compression spring 165, one end of which is supported by an I-shaped piece 166 secured to disc 161, tends to 50 press pawl teeth 167 into engagement with the teeth of the driving wheel 160.

When the magnet is deenergized and the lower part of the armature resting against stop screw 168, step 148 on the upper part of the armature 60 is in the path of the tail 169 of pawl 163, and when these parts engage, the pawl teeth disengage from those of wheel 160, thus disconnecting the motor from the rest of the apparatus. In order to prevent any back lash or rebounding of 65 the parts associated with disc 161 of the clutch on disengagement thereof, a latch is provided consisting of a flat strip of metal 170 secured by screws 171 to disc 161, which catches under the nose 172 of a spring reed 173 secured to armature 143. When the magnet is energized parts 170 and 172 disengage along with the tail of pawl 173 and the step on armature, permitting the pawl teeth to engage wheel 160. A weight 175 70 is adjustably secured to one side of disc 161 to

compensate for the weight of the pawl and other small parts adjacent thereto.

The invention contemplates the employment of a number of spare scanning cylinders 14 in their casings 36 with each receiving machine in 5 order that a spare cylinder with unexposed film will be available to insert into the receiver after the completion of each picture. A novel device is provided for loading the cylinders with fresh film which makes it possible to unload the exposed film and quickly insert the new with a minimum amount of handling of the sensitized material.

Referring to Figures 12 to 19: The loading device consists of a base 180 provided with a head stock 181 and a tailstock 182, the latter being similar to tailstock 17 of the receiver. Two strips 183 are disposed on the base to form a support and guideway for the base 39 of the cylinder casings. Strips 183 have lengthwise recesses 184 20 made in the tops thereof to form guides for the ends of base 39 which support the base at a height sufficient for the depending shutter actuating pieces 57 to clear base 180 so as not to affect the shutter when the cylinder casing is inserted. The head and tail stocks are of the proper height to engage the centers on shaft 15 and disc 11 which support cylinder 14.

The head stock consists of a bracket 185 through which extends shaft 186, at one end of which is a knob 187 and near the opposite end, adjacent to the bracket, is secured a sleeve 188 integral with disc 189 having a square notch 190 cut in its periphery. This notch cooperates with tooth 191 on the upper edge of lever 192 35 pivoted on screw 193 supported by bracket 194 which is part of head stock bracket 185. Spring 195 presses lever 192 upward against disc 189.

Beyond disc 189 is secured an arm 196 carrying a pin 197 projecting therefrom parallel with 40 shaft 186. Clamping screw 198 permits arm 196 to be locked to shaft 186 in the desired angular position. Pin 197 is adapted to fit into slot 10 of disc 11 to form a connection between knob 197 and cylinder 14, permitting the cylinder to be 45 rotated by the knob.

Figure 17 shows the cylinder and knob 197 locked against rotation by tooth 191 on lever 192 which is shown positioned in notch 190 in disc 189. The parts may be freed for rotation by 50 pressing downward on lever 192 which disengages the tooth and notch and if the disc is rotated a trifle and thereafter the lever is released, one complete turn of the cylinder may be made before the lever locks the cylinder against rotation. 55 This mechanism is used for the purpose of positioning automatically a film retaining clip on the cylinder in respect to a loading platform which will be described in detail below.

Located adjacent to the ends of casing 36 are 60 a pair of brackets 199 secured to base 180 by screws 200. Between the brackets and secured by screws 201 to steps formed thereon is a shelf 65 or loading platform 202. The upper part of casing 36 has a longitudinal opening extending the length of cylinder 14 which lines up with platform 202. The opening is provided with a curved cover 204 lined with felt 205 and hinged to the casing by hinge 206. The cover overlaps opening 203 and the edge 207 is retained when the cover 70 is closed by lock 208. The lock is formed of a metal strip attached to casing 36 by shoulder screw 209 which extends through an elongated hole in the piece 208 permitting a limited sliding movement of the strip.

- The sensitized sheet 213 is held in place on the cylinder by retaining strip 214 which extends the length of the cylinder. The retaining strip is held in place by means of springs 215 fastened between shaft 32 and studs 216 secured to strip 214. A loading tool 217 having bifurcated arms 218 which carry pins 219 which fit openings in the retaining strip is used to tilt the strip sideways in either direction for the purpose of removing or inserting film.

Extension brackets 220 are formed integrally with brackets 199 but are slightly offset therefrom so as to extend upward along the edges of the loading table 202 to form a guide for the edges of the film and to support a pressure roller 221. Roller 221 is rotatably supported by screws 222 which extend through lugs 223 depending from crossbar 224, the ends of which are yieldingly held by vertical rods 225 which pass through hollow adjusting screws 226 which are threaded into brackets 220. Roller 221 is located so that it engages the surface of cylinder parallel with shaft 32 and arm 196 is adjusted so that the retaining strip 214 just clears roller 221 during a film changing operation. Springs 227 press roller 221 against the cylinder surface, and this pressure may be varied by adjusting screws 226.

Since the operation of the various parts of the device has been described above, it is not thought necessary to repeat the same in a detailed description of the operation per se, as this will be obvious to those familiar with the art.

What is claimed is:

1. In a facsimile transmission apparatus, a base, a removable motor driven scanning cylinder on said base, a light proof casing for said cylinder, a shutter in said casing, and means for opening automatically said shutter when said cylinder is placed in position to be scanned.
2. In a facsimile transmission apparatus, a base, a removable motor driven scanning cylinder on said base, a light proof casing for said cylinder, a shutter in said casing, means for opening automatically said shutter when said cylinder is placed in position to be scanned, and means for closing said shutter automatically when said cylinder is removed from scanning position.
3. In a facsimile receiving apparatus, a base, a motor on said base, a removable scanning cylinder on said base adapted to be turned by said motor, a sheet of sensitized material on said cylinder, a scanning device comprising a source of light varying in intensity according to the light values of the elemental areas of the picture being transmitted, a light proof casing for said cylinder, a shutter in said casing, and means for automatically opening said shutter to expose said sheet to light from said source when said cylinder is placed in operating position.
4. In a facsimile receiving apparatus, a base, a motor on said base, a removable scanning cylinder on said base adapted to be turned by said motor, a sheet of sensitized material on said cylinder, a scanning device including a source of light movable longitudinally in respect to said cylinder; a light proof casing for said cylinder, a shutter normally closed in said casing, means for automatically opening said shutter when said cylinder is in operating position to expose said sheet to light from said source, and means for automatically closing said shutter when said cylinder is removed from operating position.
5. In a facsimile transmission system, a carriage, a lead screw, a lead nut secured to said carriage by a support adapted to yield in all

directions, and stop means for said nut on said carriage effective only in the direction of the thrust imparted to said nut by said screw.

6. In a facsimile transmission system, a carriage, a lead screw, a lead nut engaging part only of the diameter of said lead screw, yielding means for securing said lead nut to said carriage, and adjustable stop means on said carriage to limit the movement which said lead screw tends to impart to said nut.

7. In a facsimile transmission system, a scanning cylinder, a base therefor, a carriage disposed beneath said base, a lead screw adapted to move said carriage longitudinally in respect to said cylinder, a lead nut secured by a yielding support to said carriage, a lever extending upwardly from said carriage through said base whereby the engagement of the lead nut and lead screw may be controlled.

8. In a facsimile transmission system, a scanning cylinder, a base therefor, a carriage disposed beneath said base, a lead screw adapted to move said carriage longitudinally in respect to said cylinder, a lead nut secured by a yielding support to said carriage, a lever projecting upwardly through a slot in said base, a circular cam secured to said lever beneath said base, a rod adapted to be reciprocated by said cam when said lever is turned, said rod being adapted when reciprocated to control the engagement of the lead nut and lead screw.

9. In a picture transmission system, a carriage, a pair of oppositely disposed supporting arms on said carriage, and a lamp housing for a scanning lamp depending below said arms.

10. In a picture transmission system, a carriage, a pair of oppositely disposed supporting arms on said carriage, a lamp housing for a scanning lamp depending below said arms, and an optical system having an objective located above said arms.

11. In a picture transmission system, a base, a scanning cylinder on said base, a pair of ribs depending from the under side of said base, a runner secured to each of said ribs, a carriage having a pair of arms adapted to slide on said runners, a lamp housing depending below said arms, and an optical system having an objective supported by said carriage above said arms.

12. In a picture transmission system, a base, a scanning cylinder on said base, a driving motor, a direct drive connection between said cylinder and said motor, a scanning device having a worm drive disposed beneath said base, and shaft and gear means connecting said worm with the shaft of said motor.

13. In a picture transmission system, a base, a scanning cylinder rotatably supported on said base, a longitudinally movable carriage disposed beneath said base, an optical system carried by said carriage, a longitudinal slot in said base underneath said cylinder through which said optical system may scan said cylinder, a light proof curtain covering said slot, and an opening in said curtain into which the objective of said optical system extends.

14. In a picture transmission system, a base, a scanning cylinder rotatably supported on said base, a longitudinally movable carriage disposed beneath said base, an optical system carried by said carriage, a longitudinal slot in said base underneath said cylinder through which said optical system may scan said cylinder, a guide-way disposed beneath said base on opposite sides of said slot, a slideable metallic curtain in said slot.

guideway, and an opening in said curtain into which the objective of said optical system extends.

15. In a facsimile transmission device, a motor and a scanning apparatus, a clutch connecting said motor with said scanning apparatus, a pawl carried by the driven member of said clutch and a ratchet adapted to cooperate with said pawl carried by the driving member of said clutch; a magnet and an armature therefor for controlling the operation of said clutch, a spring tending to hold the armature away from said magnet in position to engage said pawl and to thereby cause said clutch to disengage, and a latch effective after a momentary energization of said magnet for retaining said armature out of the path of said pawl.
16. In a facsimile transmission device, a motor and a scanning apparatus, a clutch connecting said motor with said scanning apparatus, a pawl carried by the driven member of said clutch, and a ratchet adapted to cooperate with said pawl carried by the driving member of said clutch; a magnet and an armature therefor for controlling the operation of said clutch, a spring tending
- 5
10
15
20
25

to hold the armature away from said magnet in position to engage said pawl and to thereby cause said clutch to disengage, a latch effective after a momentary energization of said magnet to hold the armature out of the path of said pawl, and a push button for disengaging said latch from said armature.

17. In a facsimile transmission device, a motor and a scanning apparatus, a clutch connecting said motor with said scanning apparatus, a pawl carried by the driven member of said clutch, and a ratchet adapted to cooperate with said pawl carried by the driving member of said clutch; a magnet and an armature therefor for controlling the operation of said clutch, a spring tending to hold the armature away from said magnet in position to engage said pawl and to thereby cause said clutch to disengage, a latch effective after a momentary energization of said magnet to hold the armature out of the path of said pawl, and a yielding member carried by said armature adapted to engage a part of said driven member when the clutch is disengaged to prevent rebound of the driven member.

HAROLD CARLSON. 25
